DUMPING CAR.

APPLICATION FILED APR. 5, 1904.

NO MODEL.

UNITED STATES PATENT OFFICE.

JOSEPH D. HAMPTON, OF HAZLETON, PENNSYLVANIA.

DUMPING-CAR.

SPECIFICATION forming part of Letters Patent No. 777,020, dated December 6, 1904.

Application filed April 5, 1904. Serial No. 201,724. (No model.)

to whom it may concern:

Known that I, JOSEPH D. HAMPTON, residing at Hazleton, in the county of Luzerne and State of Pennsylvania, have invented certain new and useful Improvements in Dumping-Cars, of which the following is a specification.

My invention relates to the class of dumping-cars, and more particularly to those cars adapted for use in coal and other mines, and it more particularly seeks to provide a simple and effective dumping-car which can be simply and economically constructed and which will readily serve its intended purposes.

Generically the invention embodies a skeleton car, including fixedly-held sides and ends and a movable platform or false bottom carrying a pusher or false end at one end and which under predetermined conditions can be brought into operative connection with the drive-wheel axle whereby to move the bottom in an endwise direction to dump the contents of the car.

The invention also embodies an automatically-released gate adapted to be unlocked as the bottom is moved endwise to dump or eject all the contents of the car and to be again locked when the bottom is returned to its initial position.

With other objects in view, which will be hereinafter fully apparent, the invention consists in certain novel construction and combination of parts, all of which will be first described in detail and then specifically pointed out in the appended claims, reference being had to the accompanying drawings, in which—

Figure 1 is a perspective view of a car constructed in accordance with my invention. Fig. 2 is an inverted perspective view thereof. Fig. 3 is a longitudinal sectional view taken on the line 3 3 of Fig. 2. Fig. 4 is a similar view, the parts being in their dumping position. Fig. 5 is a cross-section on the line 5 5 of Fig. 2. Fig. 6 is a detail perspective view of the false platform looking from beneath the same.

Referring now to the accompanying drawings, in which like numerals and letters of reference indicate like parts in all the figures, the car C comprises the longitudinal and trans-

verse bottom cross-beams 1 2, to which the uprights 1^a 2^a are secured, and the longitudinal and transverse top cross-beams 3 4, secured to the uprights 1^a 2^a. 5 5 designate the sides of the car, and 6 indicates the fixedly-held end, all of which are secured to the uprights 1^a 2^a and the cross-beams in any approved manner. The said uprights may be braced by the diagonal braces 1^b 1^b, as shown in Fig. 1.

Secured to the transverse beams 2 2 is a pair of L-shaped guide-beams 7 7, which co-operate with the T-shaped rack-carrying member 10, hereinafter again referred to.

Mounted in bearings 8 8 on the longitudinal beams 1 1 are the drive-shafts 9 9, to which the drive-wheels 9^a 9^a are attached, and the said shafts 9 9 each carrying a sprocket-wheel 9^b 9^b, with which the endless chain 9^c co-operates, and one of the shafts 9 also carries a gear-wheel 9^d, disposed about midway between the drive-wheels 9^a 9^a and which co-operates with the rack 12 of the rack-carrying member 10.

The false bottom 11 is endwise movable, sliding on the longitudinal beams 1 1, and it has a pusher or false end 11^a, fixedly secured thereto at one end 11^b, while the free end 11^c of the bottom 11 projects outside the car and has secured thereto a cross-piece 11^d, which carries a pair of angle-braces 11^e 11^e, co-operating with the gate 15, which gate is hingedly secured to the cross-beam 4. The angle-braces 11^e 11^e serve to hold the gate locked to its closed position when the parts are in their normal position, as shown in Fig. 1.

The T-shaped rack-carrying member 10 consists of two parts 10^a 10^b, one of which, 11^a, is fixedly secured to the bottom 11 by the bolts α or otherwise, while the part 10^b is connected to the part 10^a by the hinges 10^c 10^c for a purpose presently to appear, and the said member 10^a has a longitudinal groove 10^d in its under side which is adapted to receive the rack 12, which is in three parts, two of which, 12^a 12^b, are carried by the member 10^a, while the other, 12^c, is carried by the member 10^b. The rack portion 10^c is fixedly secured throughout its length to the member 10^b, while the rack portion 12^b is fixedly secured to the member 10^a and has a rack portion 12^a hingedly secured to it. The groove 10^d is deepened, as

- at 10°, to receive a spring 12^a, which co-operates with the rack portion 12^a, held with its free end in the groove 10^a by the cross-plate 10^t, secured to the member 10.
- 5 11^a 11^b designate stops on the bottom 11 to limit the endwise movement thereof.
- Mounted in bearings 13 13 on the longitudinal beams 2 2 and in a bearing 13^a on the guide-beams 7 is a shaft 14, having levers 14^a 10 at each extremity thereof, which project upwardly alongside the car, the said shaft 14 being located about midway the ends of the car. This shaft 14 also carries a crank-arm 14^b between the guide-beams 7 and the beam 2, the 15 said crank-arm 14 being joined to the crank-arms 16^b of a shaft 16 by means of the rod 14^c. The shaft 16 is mounted in bearings 16^a 16^b on the guide-beams 7 7 and in advance of the gear 9^d, and the said shaft is provided 20 with a Ω-shaped portion 16^c for co-operating with the rack portion 12^a to hold it out of engagement with the gear 9^d when the parts are in their normal positions. A stop or catch 25 s is provided on the car sides to hold the lever 14^a in such a position as to maintain the Ω-shaped portion 16^c in engagement with the rack portion 12^a when the parts are in their normal position.
- If necessary, I may cover the bottom 11, 30 together with its pusher portion 11^a, with a metal sheathing 20, and I may also cover the inner sides and end walls 5 6 with a like sheathing 21, if found desirable in practice.
- So far as described the operation of my invention can be best explained as follows: 35 When the parts are in the position shown in Figs. 1 and 2, the car is ready to receive its load, the rack 12 being held out of engagement with the gear 9^d by the portions 16^c of the shaft 16 to allow of a free movement of the car, the lever 14 being in engagement with the stop s. At this time the end-gate is closed and the bottom is in position with its false end or bottom against the fixed end of the car-frame. The car after it has been loaded is 45 moved from place to place, as desired, by any suitable motor power, which may be the ordinary mule team, as used with the cars when in mines. When the car arrives at the place 50 where it is desired to unload, the attendant releases the lever 14^a, which then permits the spring 12^a to move and hold the rack portion in engagement with the gear 9^d. The car is then moved slightly forward, causing the gear 9^d to bring the bottom forward, as shown in Fig. 55 3, thereby releasing the end-gate and permitting the pusher and the bottom to carry the material contained within the car out from between the car sides. As the bottom reaches 60 the limit of its endwise movement the hinged joint y of the member 10 will be in alignment with the edge z of the cut-away portion z' of the cross-beam 2, which cut-away portion is slightly wider than the vertical portion of the 65 T-shaped member 10 to allow the bottom to tilt, as shown in Fig. 4. The hinge 10^x of the member 10 which grooves of the longitudinal gage the edges z of the beam 2. This tipping or tilting of the permit the contents thereof to slide come dumped. After the car has b or unloaded in the manner just c is only necessary to move it in the rection, when the gear 9^d will ag the bottom to its normal position, the rack is again disengaged fro by bringing the said lever into e with the stop s, it being understc the bottom returns to its normal po the car has been dumped the hang gate will be again engaged by the angion on the cross-piece attached to the bottom and lock the same from opening.
- From the foregoing description, taken in 85 connection with the accompanying drawings, it is thought the advantages and complete operation of my invention will be readily understood by those skilled in the art to which it appertains, and I desire it clearly understood 90 that slight changes in the detailed construction and arrangement of parts may be made without departing from the scope of the invention and the appended claims.
- I am aware that dumping-cars have been 95 heretofore provided in which a fixedly-held hopper is mounted upon a car-truck and with a removable bottom, and I am also aware that dumping-cars having removable sides and 100 tilting bodies have been provided, and I therefore do not broadly claim such construction; but
- What I do claim, and desire to secure by Letters Patent, is—
1. A dumping-car having fixedly-held sides and ends and a gate at one end, a movable bottom, means for automatically moving said bottom endwise to release said gate and carry the load therethrough to dump the same for the purposes specified. 105
2. A dumping-car having fixedly-held sides and ends, a gate at one end, a movable bottom having a pusher end, means for automatically moving said bottom endwise to release said gate and carry the contents of the car through 110 said gate to dump the same and for returning said bottom to its initial position. 115
3. A dumping-car having fixedly-held sides and ends, a gate at one end, a movable bottom having a pusher end, means for automatically moving said bottom endwise to release said gate and carry the contents of the car through 120 said gate to dump the same and for returning said bottom to its initial position, said means including rack-and-pinion devices co-operating with the drive-wheels and the movable bottom for the purposes specified. 125
4. In a dumping-car having fixedly-held side walls, a fixedly-held end wall and an end-gate, a longitudinally-movable bottom having a 130

pusher end, a rack carried by said bottom, said car including drive-shafts and drive-wheels therefor, a pinion carried by one of said drive-shafts for meshing with said rack and means for normally holding said rack out of engagement with said pinion.

5. In a dumping-car, a pair of drive-axles and drive-wheels therefor, sprockets carried by said drive-axles, an endless chain passing over said sprockets, a pinion secured to one of said drive-axles, said car including side and end walls and a movable bottom, a T-shaped member secured to the under side of said bottom, and guide-beams therefor, a rack carried by said T-shaped member to coöperate with said pinion for the purposes specified.

6. In a dumping-car, a pair of drive-axles and drive-wheels therefor, sprockets carried by said drive-axles, an endless chain passing over said sprockets, a pinion secured to one of said drive-axles, said car including side and end walls and a movable bottom, a two-part T-shaped member secured to said bottom, guide-beams therefor, a rack fixedly secured to one part of said T-shaped member, a second rack secured to the other part thereof, a third rack pivotally secured to said second rack and carried by said other part of the T-shaped member, said rack adapted to coöperate with said pinion and means for holding the third rack out of engagement with the pinion.

7. In a dumping-car, a pair of drive-axles and drive-wheels therefor, sprockets carried by said drive-axles, an endless chain passing over said sprockets, a pinion secured to one of said drive-axles, said car including side and end walls and a movable bottom, a two-part T-shaped member secured to said bottom, 35 guide-beams therefor, a rack fixedly secured to one part of said T-shaped member, a second rack secured to the other part thereof, a third rack pivotally secured to said second rack and carried by said other part of the T- 40 shaped member, said rack adapted to coöperate with said pinion and means for holding the third rack normally out of engagement with the pinion, said means including a shaft 45 having a portion for engaging said third rack.

50 8. In a dumping-car, a pair of drive-axles and drive-wheels therefor, sprockets carried by said drive-axles, an endless chain passing over said sprockets, a pinion secured to one of said drive-axles, said car including side 55 and end walls and a movable bottom, a two-part T-shaped member secured to said bottom, guide-beams therefor, a rack fixedly secured to one part of the T-shaped member, a second rack secured to the other part thereof, 60 a third rack pivotally secured to said second rack and carried by said other part of the T-shaped member, said rack adapted to coöperate with said pinion and means for holding the third rack normally out of engagement 65 with the pinion, said means including a shaft

having a portion for engaging said third rack, and means for forcing said third rack into engagement, with said pinion, when released, as specified.

9. In a dumping-car, comprising side and end walls, a drive-axle, drive-wheels therefor, a movable bottom, a rack-carrying member secured thereto, a second rack-carrying member hingedly secured to said first-named rack member said rack-carrying members each having an alining groove, racks held in said grooves, a pinion carried by the drive-shaft coöoperating with said racks for the purposes specified. 75

10. In a dumping-car, comprising side and end walls, a drive-axle, drive-wheels therefor, a movable bottom, a rack-carrying member secured thereto, a second rack-carrying member hingedly secured to said first-mentioned rack member, said rack-carrying members each having an alining groove, racks held in said grooves, a pinion carried by the drive-shaft coöoperating with said racks and means for normally holding a portion of said rack out of engagement with said pinion. 85 90

11. In a dumping-car, comprising side and end walls, a drive-axle, drive-wheels therefor, a movable bottom, a rack-carrying member secured thereto, a second rack-carrying member hingedly secured to said first rack-carrying member, said rack-carrying members each having an alining groove, racks held in said grooves, a pinion carried by the drive-shaft coöperating with said racks and means for normally holding a portion of said rack out of engagement with said pinion, said pinion being arranged to move said bottom longitudinally at predetermined times to dump the load, for the purposes specified. 95 100

12. In a dumping-car, comprising side and end walls, drive-wheels therefor, a movable bottom, a rack - carrying member secured thereto, a second rack - carrying member hingedly secured to said first-mentioned rack member, said rack - carrying members each having an alining groove, racks held in said grooves, a pinion carried by the drive-shaft co-operating with said racks and means for normally holding a portion of said rack out of engagement with said pinion, said means including a shaft having a portion for engaging said rack portions, said last-named shaft having a crank, a second shaft having a crank and end levers, a rod for connecting the said second shaft-crank with said first shaft-crank, said pinion adapted to move said bottom longitudinally at predetermined times for the purposes specified. 105 110 115 120

13. In a dumping-car, comprising side and end walls, a drive-axle, drive-wheels therefor, a movable bottom, a rack-carrying member secured thereto, a second rack-carrying member hingedly secured to said first-mentioned rack member, said rack-carrying members each having an alining groove, racks held in 130
125

said grooves, a pinion carried by the drive-shaft coöperating with said racks and means for normally holding a portion of said rack out of engagement with said pinion, said pinion being adapted to move said bottom longitudinally at predetermined times to dump the load, said means including a shaft having a portion for engaging said rack portions, said last-named shaft having a crank, a second shaft having a crank and end levers, a rod for moving the said second shaft-crank with said first shaft-crank, said pinion adapted to move said bottom longitudinally at predetermined times, and said bottom adapted to be tilted

after it has been moved to the farthest point 15 in its longitudinal direction.

14. In a dumping-car including drive-shafts and drive-wheels therefor, a fixedly-held side and end walls, a movable bottom and means for moving said bottom longitudinally to 20 force the contents of the car out of the end thereof, a gate for said exit end, said bottom being so arranged that it will tilt when in its projected position for the purposes specified.

J. D. HAMPTON.
